Primary Examiner — Sheryl Lane*Assistant Examiner* — Samantha N Wood(74) *Attorney, Agent, or Firm* — Michael Best &
Friedrich LLP(57) **CLAIM**We claim the ornamental design for a bicycle frame, as
shown and described.

DESCRIPTION

FIG. 1 is a perspective view of a bicycle frame embodying
the present invention.

FIG. 2 is a right side view of the design shown in FIG. 1.

FIG. 3 is a left side view of the design shown in FIG. 1.

FIG. 4 is a front view of the design shown in FIG. 1.

FIG. 5 is a rear view of the design shown in FIG. 1.

FIG. 6 is top view of the design of FIG. 1; and,

FIG. 7 is a bottom view of the design of FIG. 1.

The portions of the bicycle frame shown in broken lines
form no part of the claimed design.**1 Claim, 7 Drawing Sheets**(56)
